(57) **CLAIM**

The ornamental design for a rotating primary and secondary lamp, as shown and described.

DESCRIPTION

FIG. 1 is a perspective view of a rotating primary and secondary lamp showing my new design;

FIG. 2 is a front view thereof;

FIG. 3 is a back view thereof;

FIG. 4 is a left side view thereof;

FIG. 5 is a right side view thereof;

FIG. 6 is a top view thereof;

FIG. 7 is a bottom view thereof;

FIG. 8 is a perspective view of another state of the rotating primary and secondary lamp thereof; and,

FIG. 9 is a perspective view of further another state of the rotating primary and secondary lamp thereof.

The broken lines shown in the drawings depict portions of the rotating primary and secondary lamp in which the design is embodied, that form no part of the claimed design.
